UNITED STATES PATENT OFFICE.

LYMAN E. JACOBUS, OF ROMULUS, NEW YORK.

LATCH.

SPECIFICATION forming part of Letters Patent No. 510,176, dated December 5, 1893.

Application filed December 12, 1892. Serial No. 454,968. (No model.)

To all whom it may concern:

Be it known that I, LYMAN E. JACOBUS, of 5
Romulus, in the county of Seneca, in the State
of New York, have invented new and useful
Improvements in Latches, of which the fol-
lowing, taken in connection with the accom-
panying drawings, is a full, clear, and exact
description.

My invention relates to latches and locks, 10
combined, adapted to both securely latch or
lock a door to its post or casing, and also to
draw the same tightly against the stile, or to
draw together and latch or lock the meeting
rails of two window sashes.

15 My object is to produce a latch or lock, in
which the latching or locking lever is mounted
at one end in a universal bearing, and in-
termediate to its length is provided with a
shoulder adapted, when the lever is swung, to
20 engage with a cam upon the latch plate, sub-
stantially simultaneous with the entrance of
said lever into its recess in said latch plate,
whereby said lever is caused to draw the door,
or other article to which it is connected, in
25 the line of the lever, said latch plate being
also provided with means whereby said latch
is secured detachably in its recess in the latch-
plate.

My invention consists in the several novel 30
features of construction and operation here-
inafter described and which are specifically
set forth in the claims hereunto annexed. It
is constructed as follows, reference being had
to the accompanying drawings, in which—

35 Figure 1, is a front elevation of part of a
sliding door, as a car door, its stile and the
latch or lock in the locked and latched pos-
ition. Fig. 2, is a plan perspective of the same
40 parts, showing the latch just about to enter
the recess in the latch-plate. Fig. 3, is a sec-
tional elevation on line $y-y$, in Fig. 1. Fig.
4, is a like view on line $x-x$, in Fig. 1.

A, is a sliding door, as a car door; and —B—
is its casing, all of ordinary construction, or
45 these letters of reference may also indicate
the meeting rails of two window sash, or a
sash and part of its casing.

D, is the latch lever bearing consisting of
a block, grooved in one end upon transverse
50 lines, as at —a— and —b—, said grooves at
their intersection within the block being en-
larged so as to create a bearing for the ball

—c— upon the lever —d—, the opening —e—
is the rear face of said block being large enough
to permit the insertion of the ball from that 55
side, the shank of the lever fitting loosely in
said groove. Said lever is provided with a
transverse shoulder or lug —d'—, on one side,
and also with a handle —d''— upon its free
end, when desired. 60

E, is the latch-plate, comprising a back-
plate —h— tapering toward the top and cre-
ating the cams —h'— on opposite sides, so as
to be right or left-handed, and having a brack-
et-like projection and arm —h''— creating 65
the latch-lever recess between it and the back
plate; so that when said lever is forced down
into said recess, its shoulder will engage with
one of said cams, and draw the door toward
the casing, until, when tight, the lever is seated 70
in said recess. As a means of holding said
lever therein, a pawl —m— is pivoted in or
upon said bracket arm, its beveled point pro-
jecting into said recess, so that it is swung by
the entrance of the lever, and by gravity as- 75
sumes the position shown in Fig. 4, when said
lever passes it, its projecting point then serv-
ing to retain said lever in its seat, until the
pawl is operated by hand to release it.

It will be readily seen that if the lever is 80
dropped to a vertical position as shown by the
dotted lines in Fig. 1, it can then be swung
into any of the grooves, so that it and said
block, are also right and left-handed. Said
block can also be made in two pieces, if de- 85
sired, with part of the ball bearing in each,
as indicated by the dotted line r in Fig. 2.

The grooves —a— and —b— are cut, or cast,
into the block in such manner that they in-
tersect each other, each being open outwardly, 90
and of such size as to freely receive the shank
of the latch-lever, its head —c— having its
bearing at their intersection and is rotatable
therein. In Figs. 1, 2 and 3 the lever is shown
as projecting to the right, to lock the right- 95
hand edge of the door, its strain being on a
line transverse to the screws which hold the
block in place. To lock the left-hand edge of
a sliding door, the block and latch-plate be-
ing mounted in proper relation upon the door 100
and casing, the lever is allowed to drop to a
vertical position, as shown by the dotted lines
in Fig. 1, and is then swung upward to the
left and into the groove —b— on that side

and the latch-lever will then project to the left upon a line transverse to the block-securing screws; and to lock a swinging door, the block is secured upon the door, the latch-plate 5 being secured upon the inner face of the door-post, and the latch-lever is swung from the pendent position, forward or outwardly into the slot —a— and will then stand substantially at a right-angle to the door, and in a line substantially parallel with that of the axes of the block-securing screws. From this 10 it will be seen that the latch is universal, in that it can be set up and operated, right or left handed, or to the front, to lock either 15 sliding or swinging doors.

What I claim as my invention, and desire to secure by Letters Patent, is—

1. A latch or lock, comprising a bearing block, provided with transverse grooves substantially as shown creating a bearing therein, a latch lever having a bearing therein and adapted to be shifted from one slot to another and a latch plate recessed to receive said lever, in combination.

25 2. A latch or lock, comprising a bearing

block, provided with transversely intersecting grooves creating a universal bearing therein, a latch lever having a bearing therein and adapted to be shifted from one slot to another, a shoulder upon said lever, and a latch-plate 30 recessed to receive said lever, and having a cam face, with which said shoulder engages, in combination.

3. A latch or lock comprising a bearing block, provided with transversely intersecting 35 grooves creating a universal bearing therein, a latch lever having an end bearing therein and adapted to be shifted from one slot to another and retained therein by the lateral walls thereof, a shoulder upon said lever, and a 40 latch-plate recessed to receive said lever, and having a cam face, with which said lever engages, and means to detachably secure said lever in said recess, in combination.

In witness whereof I have hereunto set my 45 hand this 1st day of December, 1892.

LYMAN E. JACOBUS.

In presence of—

HOWARD P. DENISON,
C. B. KINNE.
